SIGNALING CIRCUITS

Richard F. Spamer, Lynbrook, N. Y., assignor to
 American District Telegraph Company, New
 York, N. Y., a corporation of New Jersey

Application April 5, 1938, Serial No. 200,146

9 Claims. (Cl. 177—367)

This invention relates to signal systems, and more particularly to signal systems of the type wherein a number of watchman's tour systems or fire alarm systems are connected to a central station. It is customary in these systems to have several protected premises connected to a central station wherein an attendant can supervise watchmen or fire stations in the several premises. Each watchman periodically sends signals to the central station where they are recorded and operate various indicators so that the attendant may supervise the system.

This type of service is no longer adequate in many instances because subscribers to the service frequently require that they themselves be able to supervise their protective systems or watchmen either by a record or other indication of the watchman's activity during the tour of duty. However, since there are a number of subscribers connected on a single line to the central station, the system must provide a signaling or recording means at each subscriber's premises wherein only the local signals or subscriber's watchmen will operate each subscriber's recording means as signals are transmitted to the central station. In a system embodying the invention, therefore, each subscriber's station is provided with a device for operating his own local signal, alarm or recorder when a signal is transmitted from his own premises, but this same device will not allow any other subscriber's signals to be recorded or actuate the signal. It is further provided that any abnormal condition of the transmission line, which is of such a nature that signals can still be received at the central station, must not prevent the normal and exclusive acceptance of the signal on the transmitting subscriber's local recording or indicating apparatus.

It is an object of this invention to provide a watchman's supervisory system or a fire alarm system which will accomplish the results outlined above.

Another object of this invention is to provide a signal system wherein a plurality of subscribers use a central station supervisory service and wherein each subscriber obtains a record or indication of the signals transmitted from only his premises to the central station.

Another object of this invention is to provide a watchman's signal system or a fire alarm system wherein a plurality of subscribers are connected to a central office by a signal transmission line and wherein local signals from transmitters in the subscriber's premises are automatically recorded therein, but such signals do

not under any circumstances actuate the local recorder or alarm of any other subscriber.

A further object of this invention is to provide a signal system wherein a differential relay 5 distinguishes between signals from a subscriber's transmitters and those from a remote transmitter so that the local signals are automatically detected or recorded in the subscriber's premises to the exclusion of signals from other subscribers' stations.

A still further object of this invention is to provide a signaling system wherein any abnormal condition of the transmission line, which is of such a nature that signals can still be received at the central office, will not prevent the normal and exclusive acceptance of the signal on the transmitting subscriber's local apparatus.

Further objects of this invention will be apparent after consideration of the following description of the various embodiments shown in the drawings wherein:

Fig. 1 shows a complete signal system according to the invention;

Fig. 2 shows a modification of a subscriber's circuit; and

Fig. 3 shows another modification of a subscriber's circuit.

Fig. 1 of the drawings shows the general layout of a McCulloh signaling circuit, particularly 30 adapted for use in fire alarm systems, sprinkler or valve supervisory systems or night watch systems. The apparatus shown to the left of the line A—A is the conventional central office equipment used in McCulloh circuits, while everything shown to the right of the line A—A pertains to the subscribers' circuits. Numerals I, II and III indicate generally the subscribers' circuits which consist of a differential relay 27 and the impulse wheels 32, 34 and 37 for transmitting 40 the McCulloh signals to the central station where they are recorded on recorders 20, 21 of the conventional type. In order to save wiring, the substation circuits are arranged in series in the transmission line. Thus a circuit may be traced from the central office through line 23, coils 28, line 29, contacts 35 and 36, the other local transmitting stations, line 31 and coil 39 of the differential relay 27, and so on, through the subscribers' premises. This arrangement 50 gives the subscriber a record on a local recorder 45 of the activity of his watchman or in the case of a fire alarm system, there will be a record of whatever alarms are transmitted and any other desirable information. This feature of local signaling introduces a problem due to the series

arrangement of the subscribers' stations since it is imperative that no remote subscriber shall receive the local signals of subscriber I, for instance. The differential relay 27 of station I eliminates the difficulty of local and exclusive recording of the subscriber's local signals.

The circuit is shown in normal condition where switch 19 completes a circuit to the ground side of the battery so that relays 1 and 3 are normally energized. When a watchman sends in his routine or emergency signal, he operates the transmitter wheel 32 for instance to thereby first ground the line 23 and then open the line at contacts 35-36. When the ground is put on the line, a circuit can be traced from ground at the subscriber's station through line 38, contact wheel 32, contact 35, line 29, coil 28, line 23 to the central station and line relay 3 to battery 43 and ground. The coil 30 is short circuited so that the differential relay is unbalanced and the coil 28 will actuate armature 40 and signal recorder 45, whereby the subscriber obtains a record of the watchman's signal. When the line circuit is opened, the line relays operate the recorders 20 and 21 by dropping their armatures. Dropping of the armatures connects the recorder 20 to battery 12 through lines 8 and 15 while recorder 21 is connected to the battery 13 through lines 13 and 17. Assuming that a watchman in the premises of subscriber II should operate a transmitter wheel, a ground signal will be transmitted from the substation through line 25, coil 30 of differential relay 27, line 31, through the transmitter contacts of subscriber I's station, coil 28 of differential relay 27, line 23, and line relay 3 as above. The signal from this substation will not be recorded in the premises of the subscriber I since coil 30 of differential relay 27 is wound oppositely to coil 28 and consequently the armature 40 will not be attracted.

From the above description it is easily seen that any number of subscribers' stations can be connected to the transmission line by means of the differential relays so that each subscriber will obtain his own signal locally but no other subscriber will receive that signal. All subscribers' stations operate in the manner set forth above.

An additional feature of the invention provides a means of automatically testing ground wires, and this is a desirable feature since in the McCulloh system under certain line circuit trouble conditions, a local transmitter can send signals to the central office only through grounding the line at the code wheel whereas normally the signal is received when the wheel opens and closes the line circuit. Therefore, when the differential relays are caused to operate by grounding the line circuit through them at a signal wheel a signal is received at the central office but is not recorded on the subscriber's local apparatus. The subscriber's watchman should notify the central station of the failure. The central station attendant would thereby know of the existence of a fault in the ground wire of the transmitter which was operated. For instance, when the transmitter wheel 32 operates but does not ground the transmission line, the line is opened and closed at contacts 35 and 36 whereby armature 40 of relay 27 is not picked up so that there is no recording of the signal in the local subscriber's premises.

Further should the transmission line become grounded, the central station attendant can determine definitely the location of the fault, i. e.,

it can be determined whether it is on the line itself or within a subscriber's premises. For example, if a ground occurs on the transmission line it cannot possibly affect the local recording apparatus at any subscriber's premises while if the fault is within any premises, the local differential relay will remain continually operated and the recording device accordingly. Under such circumstances the subscriber's watchman would notify the central station attendant of the continued operation of his local recorder and therefore the central station attendant would know that there must be a ground fault at that particular location. Also should a transmitting device stick so as to permanently ground the line, the central station attendant can, by referring to his time records for the particular subscriber, determine the exact transmitter in trouble.

The above description has been based on the assumption that all line conditions are normal, with the central office equipment shown in the drawings as McCulloh equipment in normal condition. Therefore it is necessary to consider the operation of the system under various conditions of line trouble. In order to illustrate the performance of the differential relays under abnormal conditions, it is necessary to assume typical values of resistance for various parts of the circuit. The resistances 41 and 42 in the central office ordinarily have a value of approximately 700 ohms each, while the line relays 1 and 3 may be 150 ohms each. The line circuit may be assumed to have a resistance of approximately 1000 ohms which is equivalent to a 14.3 mile loop of No. 22 gauge copper wire and the differential relays at each substation may have a resistance of approximately 20 ohms.

It may be assumed that a ground condition occurs on the transmission line between substations I and II and that the central office panel is switched for McCulloh operation in response to the ground indication received at the control station, whereby switch 19 will be thrown to the right hand contact, switch 16 will be thrown to the left hand contact and switch 11 will be thrown to the right hand contact. Thus, when a signal is transmitted from substation I, the line relay 3 will release when the line is open at the subscriber's transmitter wheel contacts to thereby record the signals and there will be a ground current of approximately .079 amp. through the transmitter wheel 32, contact 35, coil 28, line 23, relay 3 to battery 43 and ground, while there will be no current through the relay coil 30 of differential relay 27 since it will be short circuited by the ground momentarily established at break-wheel 32, contact spring 33 to the ground fault. Therefore the local signal apparatus 45 will be operated in a normal manner but no other subscriber's signal apparatus will operate. In the event that substation III is operated the open line at the transmitter contacts will cause the relay 1 to release armature 2 and connect recorder 20 to battery 12 and ground through lines 8 and 15, thereby causing the signal to be recorded in recorder 20. There will also be a ground current of about .060 ampere through the coil 230 of the differential relay and no currents through the other coil 228 of the relay in substation III whereby the local signaling apparatus will operate. It should be noted here that the differential relays continue to operate in the same manner as during normal line conditions, that is, the local signal apparatus of the transmitting

local subscriber is always operated to the exclusion of any other subscriber's local signals.

It may now be assumed that a break in the transmission line occurs between substations II and III. Therefore the switch 11 at the central office must be thrown to the left hand contact while switch 16 is thrown to the right hand contact and when the transmitter wheel at substation I is operated, the breaks in the line circuit will no longer operate the line relays but ground impulses in the line circuit will operate the line relay 3 at the central office to pick up armature 6, connecting recorder 21 to battery 18 and ground through lines 14 and 17 to operate the recorder 21, the ground circuit being the same as during normal line conditions. Substation II will also operate in the same manner. However, substation III will operate the line relay 1 when the line circuit is grounded at the transmitting wheel. In this case, however, the coil 230 is energized by the ground impulse to operate the local signal circuit.

It may next be assumed that a ground occurs in the line circuit between substations I and II and that a break in the line occurs between substations II and III. In this case the switches 11 and 16 at the central station are both thrown to the left hand contacts. When the transmitter wheel of substation I is operated, the line relay 3 will operate on the break impulses as under normal conditions and the coil 28 of differential relay 27 will operate the local signal apparatus. Signals from substation No. II will not operate the central station apparatus under any conditions. When substation III is operated no signal will be transmitted over line 23, but a ground impulse will be transmitted through coil 230 to operate the relay 1 at the central office and connect battery 12 to the recorder 20 through lines 7 and 15.

From the above discussion of various line conditions it is evident that the system constructed in accordance with this invention will include the operating advantages of the usual McCulloh systems. However, due to the use of the differential relay 27 and similar relays at all substations, it is found that under any conditions each subscriber obtains local indication of the performance of his particular circuit to the exclusion of all other circuits which may be connected in the system.

Fig. 2 shows a modification of the subscriber circuit wherein the transformer 50 is substituted for the relay 27 shown in Fig. 1. The primary windings 51 and 52 of the transformer 50 are connected to lines 23 and 25 and to the transmitter wheel whereby the same effect is obtained as was obtained with relay 27 in Fig. 1, that is, windings 51 and 52 are connected in opposition so that signals transmitted from other subscriber's stations will not actuate the local recording or signaling apparatus. The secondary windings 55 and 56 are connected through lines 57 and 60 to the vacuum tube amplifier 64 which is in turn connected to the slow release signal operating relay 68. When the impulse wheel 32 is operated by the watchman, contacts 35 and 36 ground the line at 38 and also open the line to operate the central office equipment. The transformer will then become operative since the positive ground signal pulse is transmitted through only winding 51 and thereby energizes the windings 55 and 56 of transformer 50. These windings in turn impress a positive pulse across resistance 61 to ground 62 to bias the amplifier

64 to an operative condition and thereby energize slow release relay 68. The armature 69 of relay 68 in turn operates to energize recording or other indicating apparatus connected to circuit 70. Relay 68 is of the slow release type because the output of the tube 64 is only a pulse and the armature 69 would quickly drop off. Furthermore, when ground is removed at the signal wheel, a second pulse occurs of opposite direction to the first, the grid becoming less positive and the armature 69 tending to drop off. In view of the above, the relay 68 must be slow to release.

Fig. 3 shows a different modification of a subscriber circuit wherein a Wheatstone bridge is substituted for the differential relay 27. The impulsion mechanism 32 is connected to lines 23 and 25 through the Wheatstone bridge which comprises resistances 80, 81, 82 and 83. Resistances 80 and 81 may be of the order of one megohm each while resistances 82 and 83 may be of the order of two ohms each. Amplifier 64 is connected to the midpoint of resistances 80 and 81 by line 85 and to the two resistances 82 and 83 by the conductor 86. Thus, when a signal is transmitted from another substation through resistances 80 and 81 the bridge will remain balanced and no signal will be impressed on amplifier 64. However, when the transmitter wheel 32 is operated, a ground signal will be transmitted through resistance 82 to unbalance the bridge circuit and therefore impress a potential on resistance 81 and on the grid of amplifier 64 which in turn operates slow release relay 68, armature 69 and the recording or indicating apparatus in the subscriber's premises which is connected to the circuit 70. In Figs. 2 and 3, other transmitters may be connected across circuit 59, as shown in Fig. 1, so that each subscriber will have a plurality of transmitters. Relay 68 must also be slow to release in the circuit shown in Fig. 3 because the relay armature 69 would tend to drop off after the break wheel opens the line and the grid of tube 64 becomes less positive.

In all of the systems illustrated on the drawings, the transmitters 32, 132, 232 et cetera, may be automatically operated in a manner obvious to those skilled in the art in response to any condition or operation which it is desired to supervise, such as fire conditions, the opening or closing of valves and the like.

From the above description it is evident that this invention provides a McCulloh signaling system wherein a plurality of subscribers are connected to a single transmission line and where each subscriber has a recording or indication of his own signals to the exclusion of all other subscriber's signals. Other modifications of this invention may be made in the construction and arrangement of parts without departing from the spirit of the invention set forth in the appended claims.

I claim:

1. In a signal system, a central station, a plurality of substations, a line connecting said substations to said central station, each of said substations comprising a differential relay having a pair of oppositely wound coils connected in series with said line, a plurality of pairs of contacts connected in series with said coils, means for actuating said contacts to ground and break said line through one of said coils and a signal adapted to be energized by said grounded coil.

2. In combination, a central station including an indicator, a transmission line connected to

the central station, a plurality of substations connected in the transmission line, transmitters connected in said substations for transmitting signals to actuate the indicator, a local signal indicator in at least one of said substations, means connected to the transmitter in said one substation and energized by local signals for controlling the local signal indicator in response to locally transmitted signals and means connected to the line at each substation for counteracting the effect of the local indicator controlling means when line signals are initiated at another substation.

3. In a signal system, a central station, a transmission line connected thereto, a plurality of subscriber substations connected to said line, each station comprising a plurality of transmitter wheels, a pair of contacts adapted to be controlled by each transmitter wheel and a differential relay, each coil of which is connected in series with said contacts and said line, signal means connected to each of said relays and means for grounding one coil of said relay whereby the local signal means will be operated and other subscribers' signal means will not be operated.

4. In a signal system, a central station, a plurality of substations, a transmission line connecting said substations to the central station, a transmitter wheel in each substation, a ground connection to each of said wheels, a pair of contacts connected in said line and controlled by said wheels to break said line and ground one side thereof, a differentially wound relay in one of said substations each of the coils of which are serially connected in said line and to one of said contacts in said one substation, whereby one of said coils is energized to ground by the local transmitter and both of said coils are energized by signals initiated at another substation, and signal means adapted to be energized by the grounded coil.

5. In a signal system, a central station adapted for McCulloh operation, a plurality of recorders in said central station, a plurality of substations, a line connecting said substations to said central station, each of said substations comprising a differential relay having a pair of oppositely wound coils connected in series with said line, a plurality of pairs of contacts connected in series with said coils, impulse means for grounding and breaking said line through one of said coils to operate said recorders at the central station and a signal adapted to be energized by said grounded coil.

6. In a signal system, a central station, a trans-

mission line connected thereto, a plurality of substations connected to said line, each station comprising a transmitter for sending signals to the central office, a local signal in at least one substation, means in said one substation for controlling the local signal comprising the primary coil of a transformer connected in said line and to said transmitter and a secondary coil connected to the local signal and means for counteracting the effect of said primary coil comprising a second oppositely wound coil connected in said line whereby line signals originating in another substation do not operate the local signal.

7. In a signal system, a central station adapted for McCulloh operation, a transmission line connected thereto, a plurality of substations connected to said line, each station comprising a plurality of transmitter wheels, a pair of contacts adapted to be controlled by each transmitter wheel and a transformer connected to said transmission line, said transformer comprising a pair of oppositely wound primary coils connected to said contacts, a pair of secondary coils, an amplifier connected to said secondary coils and means connected to said amplifier for operating a local signal.

8. In a signal system, a central station, a transmission line connected thereto and a plurality of substations connected to said line, each substation comprising a transmitter for sending signals to the central station and at least one of said substations also comprising a balanced Wheatstone bridge connected at two of its conjugate points to said line, a local signal connected across the other two conjugate points of said bridge whereby signals initiated at other substations do not operate the local signal, the transmitter of said substation being connected in one leg of said bridge whereby locally transmitted signals unbalance said bridge and operate the local signal.

9. In combination, a central office including an indicator, a transmission line connected to the central office, a plurality of substations connected in the transmission line for transmitting signals to actuate the indicator, a local signal indicator in each substation, means in the transmission line and in the substation energized by local signals for controlling the local signal indicator in response to locally transmitted signals and additional means in the line at each substation for counteracting the effect of the first means when the line signals are initiated in another substation.

R. F. SPAMER.
